UNITED STATES PATENT OFFICE

SOLOMON SHEFRAS, OF LONDON, ENGLAND

DESIGN FOR AN AMUSEMENT-DEVICE CASE

Application filed October 17, 1929. Serial No. 33,076. Term of patent 3½ years.

To all whom it may concern:

Be it known that I, SOLOMON SHEFRAS, a subject of the King of Great Britain, residing at London, England, have invented a new, original, and ornamental Design for Amusement-Device Case, of which the following is a specification, reference being had to the accompanying drawing, forming part thereof.

The figure is a perspective view of the amusement device case, showing my new design.

I claim:

The ornamental design for an amusement device case as shown.

SOLOMON SHEFRAS.
